CLAIM

The ornamental design for a fascia-mounted roof ventilator, substantially as shown and described.

DESCRIPTION

FIG. 1 is a top plan view of a fascia-mounted roof ventilator showing our new design, the article being shown broken-away to indicate indeterminate length;

FIG. 2 is a vertical transverse sectional view thereof, taken along line A—A of FIG. 5;

FIG. 3 is a right end elevational view thereof, the left end being a mirror image;

FIG. 4 is a front elevational view thereof;

FIG. 5 is a rear elevational view thereof;

FIG. 6 is a bottom plan view thereof;

FIG. 7 is a fragmentary top perspective view thereof; and

FIG. 8 is a fragmentary bottom perspective view thereof.
